UNITED STATES PATENT OFFICE

2,458,241

POSTHOLE DIGGER

Lester E. Beck, Danville, Iowa

Application July 31, 1944, Serial No. 547,432

4 Claims. (Cl. 255—22)

1

The present invention pertains to improvements in mechanism for making vertical holes in the earth's surface, primarily for use in the building of fences but not necessarily restricted to that use. For example, this apparatus may be used in the boring of holes for telephone and telegraph poles. Other uses may also be found for it, such as for the making of holes for the introduction of blasting charges for the breaking up of hardpan when preparing to plant an orchard.

One of the purposes of my present invention is to provide an apparatus of the character indicated in which the auger will be power driven, not only for rotation thereof but also for the raising and lowering of the auger. Another purpose of this invention is to provide an apparatus of the character indicated which may be driven from the power plant of the tractor, thus avoiding the necessity of providing a second power means on the tractor. Another object of this invention is the provision of a light weight, inexpensive, simple construction which can be operated by one man, without the necessity of having a helper. Still another object of this invention is the provision, in an apparatus of the character indicated, of a safety mechanism such that the lifting of the auger will be automatically stopped before, or at the time, the auger reaches its highest point, at which, if operation were continued, injury might result. My invention further comprises improved means for raising and lowering the auger in a construction of the class indicated. My invention further resides in the combination, construction, and arrangement of parts illustrated in the accompanying drawings and, while I have shown therein what is now regarded as the preferred embodiment of this invention, I desire the same to be understood as illustrative only and not to be interpreted in a limiting sense.

In the drawings annexed hereto and forming a part hereof,

Fig. 1 illustrates a front end view of a tractor having my present invention applied thereto;

Fig. 2 illustrates a rear elevation of the structure shown in Fig. 1, parts of the tractor being omitted;

Fig. 3 shows a plan view of the structure illustrated in Figs. 1 and 2, parts of the tractor being omitted;

2

Fig. 4 represents a left side elevation of the structure shown in Fig. 3;

Fig. 5 represents a fragmentary horizontal section taken approximately along the plane indicated by the line 5—5, Fig. 2; and

Fig. 6 represents a fragmentary vertical section taken approximately along the plane indicated by the line 6—6, Figs. 1 and 2.

Reference will now be made in greater detail to the annexed drawings for a more complete description of this invention. In these drawings, the numeral 1 indicates an ordinary commercial tractor of a well-known type, numeral 2 indicates the auger, and numeral 3 a belt pulley on the power take-off shaft at the right hand side of the tractor. It is not necessary to go into a detailed description of the parts thus far mentioned.

Secured to the right hand side of the tractor frame is a supporting frame 4 which has at its upper end a bearing 5 for one portion 6 of a drive shaft whereby the auger 2 is operated. On the outer end of this shaft section 6 is a belt pulley 7 which is connected by a belt 8 with a pulley 3 on the power take-off shaft. A universal joint 9 of any approved type may be used to connect the shaft 6 with the shaft section 10. This latter is preferably of a non-circular type and fits slidably in a shaft section 11 which is, in turn, connected by a universal joint 12 to the shaft section 13. On the inner end of this shaft section 13 is mounted a beveled pinion 14 which meshes with a gear 15. The gear 15 is slidably mounted on the hollow shaft or sleeve 16 whereby to permit it to be moved into and out of engagement with the pinion 14. This motion is accomplished by means of a wedge-shaped member 17, cooperating with an inclined surface on the under face of the member 18 interposed between the wedge-shaped member 17 and the gear 15. A link 19 connects the wedge-shaped member 17 with a crank 20 formed on a shaft 21. The shaft 21 passes through a rigidly mounted bracket 22 on the crossbar 23, which constitutes a part of the tractor, and through a bracket 22a whereby it is steadied. The shaft 21 has a universal joint 21b which constitutes a part thereof and relieves strain on the shaft as the auger and its suspension means move toward and away from the tractor during use.

50. The electric lamps of the tractor, indicated at

24, are adjustably mounted to be moved to desired positions on the bar 23. The rod 25 is loosely mounted in the bracket 22. The rod or shaft 21 has a handle 21a by means of which it may be operated to cause the crank 20 to separate the gear 15 from the pinion 14 in the manner described above. When the rod or shaft 21 is rotated through one hundred eighty degrees (180°), the crank 20 pulls the link 19 and, through this, the wedge-shaped member 17, so as to permit the gear 15 to drop out of mesh with the pinion 14, gear 15 sliding on sleeve 16 when released by movement of the wedge-shaped member 17.

Shaft or lever 25 may be turned vertically and horizontally about its point of contact with the bracket 22, as a pivot, and the forward end of the lever, which is secured in the end of the latch 27, may lift this end and, by horizontal movement, cause the latch to move lengthwise. As shown in Fig. 2, the latch 27 has pawls 28, 29 pivotally mounted thereon and spring-pressed into engaging position such that one or the other of the pawls engages the ratchet 30, as will be obvious from Fig. 2. These pawls serve as latching means for the ratchet 30 when the latter is rotated, either to the left or the right. The left end of the latch 27, as viewed in Fig. 2, is pivotally connected to the lower end of the link 31 which is pivotally mounted upon the frame member 32. Therefore, as the latch 27 is moved toward the left or right, it causes a corresponding swinging of the lower end of the link 31. Intermediate the two ends of the link 31, at 33, is pivotally connected a lever 34 carrying a pair of pivotally mounted pawls 35, 36.

The end 37 of the lever 34, as shown in Fig. 2, extends through a block 38, in which it is rockably supported, and which is connected by means of a link 39 to a crank pin 40 on the pulley 41. This pulley is connected in driving relation by a belt 42 to a pulley 43 on the shaft 13. From what has been said, it will be realized that rotation of the shaft comprising the parts 6 and 9 to 13, inclusive, will cause rotation of the pulleys 41 and 43 and this will, in turn, cause reciprocation of the link 39, causing oscillation of the block 38 and lever 34. When the parts are in the position shown in Fig. 2, the pawl 35 will cause counterclockwise rotation of the ratchet 30; since lifting of the end 37 of lever 34 will cause pawl 35 to engage in a higher notch in the ratchet 30. Then, as the lever 34 goes down, it will cause rotation of the ratchet. As this is stepped forward, the pawl 28 engages in the notches of the ratchet 30, preventing backward rotation thereof. This operation causes downward feeding of the auger.

The ratchet 30 is mounted on a shaft and is connected by this shaft to a sprocket 44 which engages in the links of the chain 45 secured to the square bar 46. This bar is secured at its lower end, by a suitable bracket 47, to the auger 2. The auger has a squared shaft 49 which extends upwardly through the drive gear 15 and the sleeve 16, by which the auger can be rotated.

An angle bracket 50 is mounted on the supporting frame 4 and furnishes a support for the front end of the lever 51. On the rear edge of the bracket 50 is a ratchet 52 which cooperates with ratchet mechanism 53 provided with a controlling handle 54. As will be seen in Fig. 3, there is a lug 55 projecting from one edge of the lever 51 and this is connected by a link 56 to a generally A-shaped frame 57. A bracket 58 is secured to the left side of the tractor and the arms of this

5 bracket are pivotally connected at 59 to the arms of the frame 57. This is shown most clearly in Figs. 3 and 4. At its top, the frame 57 has a horizontal crossbar 60 which is pivotally connected to the upper ends of the side members of the frame 51. Extending toward the right side of the tractor from the bar 60 is a bracket 61 which, as shown in Figs. 1 and 2, is connected to the frame 32. The double U-bolt connection 64 suspends the auger in such a manner that it is free to swing in any direction and will therefore assume a substantially vertical position when free to move. The auger is provided with a removable tip 66 which has a cutting blade 67 removably secured thereto so that it may be removed and sharpened when desired. The tip 66 may be removed by removing one or more bolts 68, shown in Fig. 4.

20 A safety mechanism is provided to keep the operator from breaking the machine by continuing the lifting of the auger after it has been raised as far as it should go. This comprises a lever 70 pivotally mounted upon sleeve 46a, shown in Fig. 5, and having a rod 71 depending from one end to be engaged by the auger-suspending head 72, when the latter reaches the safety limit of its upward motion. Suspended from the second end of the lever 70 is a stop 73 which prevents the pawl 36 from engaging the ratchet 30 when raising of rod 71 causes lowering of stop 73 into a position to obstruct the access of pawl 36 to ratchet 30. Under such circumstances, the pawl 28 will engage the ratchet and prevent lowering of the auger but continued actuation of the link 39 will merely cause the pawl 36 to slide up and down on stop member 73 without engaging and actuating the ratchet 30 and, through it, the sprocket 44. The stop member 73 is normally lifted out of its pawl-stopping position by a spring 73a when rod 71 is not raised by the head 72. A pair of arms 72a are straddled by U-bolts 76 which pass through the plate 75 and connect this to the arms and, hence, to the head 72. The plate surrounds the auger shaft and moves vertically therewith.

25 An angled frame member 77 is secured to the top of the frame 32 and extends downwardly at the right hand side thereof as shown most clearly in Fig. 2. This downwardly extending portion 50 is indicated by the numeral 78. A bracket, shown at 79, extends laterally from the part 78, as shown in Fig. 3, and is provided with an opening to receive the block 38 and guide it in its vertical motion. The lower end portion of the bracket 55 79 is slotted for the reception of the link 27 which is provided with a notched lower edge, as indicated at 80. These notches and the lower edge portion of the bracket 79 cooperate in holding the link 27 in adjusted position as the link 60 is moved from position to position by the rod 25 to change the direction of translation of the auger 2.

30 It is desired to note that, because of the positioning of the feed pawls 35 and 36, the rate of downward feeding of the auger is considerably slower than the rate of retraction thereof. This is apparent from Fig. 2 from which it will be seen that the ratchet 30 will be, ordinarily, stepped forward only one notch at a time by the pawl 70 35, whereas, when the pawls 35 and 28 are shifted out of engagement with the ratchet 30 and the pawls 29 and 36 are shifted into engagement, then each oscillation of the lever 37 will produce a greater retractive movement for each oscillation 75 of the lever 37. It is also to be noted that the

position of the pin 40 on the pulley 41 may be varied by having more than one hole for the reception of the pin, these holes being placed at different distances from the center of the pulley. Thus, the length of stroke could be changed which would change the rate or speed of retraction of the auger.

As shown clearly in Fig. 3, the plate 77a is provided with slots which, upon loosening the bolts passing through these slots, permit the relative longitudinal adjustment of the plate 77a with relation to the frame 77. This permits adjustment of the auger with relation to the supporting frame of which the arms 57 form a part, thus making it possible to compensate for changes in weight of different sized augers used, whereby to be sure that the auger will hang vertically.

Operation

Assuming that the operator of the machine has finished the making of a hole and is ready to go to the next location, he has the auger in elevated position, as shown in the drawings. He then drives the tractor to the new location and, if the auger is inwardly or outwardly from the exact position indicated for the hole, he releases the ratchet mechanism 52, 53 and swings the lever 51 to the right or left which swings the frame 57 toward or away from the tractor. This causes corresponding movement of the auger 2. If the latter is too far forward, or not far enough, he moves the tractor until he can lower the auger to the exact position indicated. The ratchet mechanism 52, 53 will hold the frame 57 against any lateral swinging motion. Having located the auger satisfactorily, the operator next grasps the handle 21a of shaft 21 and turns it to cause the wedge-shaped member 17 to force gear 15 into engagement with pinion 14. Next the lever 25 is moved, first to raise the bar 27 and then to move it longitudinally so that the middle notch 62 will engage the lower end 79 of the downwardly extending part 78 of frame member 77. This releases pawls 28, 29, 35, and 36 from the ratchet 30 which permits the auger 2 to descend, the point of the auger penetrating the ground and serving as a guide for the auger while the boring is taking place. When the point of the auger enters the ground, the lever 25 is moved over to the first notch so that the pawls 28 and 35 engage ratchet 30. Then, as shaft 9, 10, 11, 12, 13 rotates, it causes lever 37 to oscillate vertically, resulting in rotation of the ratchet 30 and downward movement of the chain 45 and bar 46. This downward motion of the bar 46 forces the auger 2 into the ground, aided by the blade 67. Rotation of the auger is started by causing engagement of the tractor clutch, which causes rotation of the shaft 9, 10, 11, 12, 13.

After the desired depth has been reached, the tractor clutch is released so that operation of the mechanism is stopped. Next, the handle 21a is turned to release gear 15 from pinion 14 so that the auger will not rotate when being lifted from the ground. Next, the lever 25 is moved to bring the end notch 80 into engagement with part 79, thus causing pawl 36 to engage ratchet 30. The parts are now positioned to cause lifting of the auger when lever 37 is oscillated. Now, when the tractor clutch is put into engagement, the ratchet 30 will be rotated in the opposite direction and will lift the chain 45 and bar 46, thus lifting the auger out of the hole. When it reaches its upper limit of motion, the lever 70 and parts associated

therewith will hold the pawl 36 away from the ratchet 30 and will thus stop the lifting motion. The pawl 29 being in engagement with the ratchet 30 prevents downward motion of the auger. Before moving to the next location, it is desirable to throw the clutch out of engagement so as to stop the rotation of shaft 9, 10, 11, 12, 13. Everything is now ready for moving to the next location.

- 10 It will of course be understood that the specific description of structure set forth above may be departed from without departing from the spirit of this invention as set forth herein and in the appended claims.
- 15 Having now described my invention, I claim:
1. In a digger of the type indicated, means for adjustably mounting a vertically reciprocating auger upon the side of a tractor, an auger carried by said mounting means, and means for raising and lowering said auger, the last mentioned means including a chain secured to the auger, a sprocket carried by the supporting means and engaging the chain for moving the auger lengthwise, and operating means for rotating the sprocket,
- 20 the operating means for the sprocket comprising a lever pivotally mounted at one end, carrying a pair of spaced pawls pivotally connected to the lever intermediate its ends, a ratchet fixedly connected to the sprocket, and mechanism for pivotally oscillating the lever about its end pivot in a vertical direction, with one of the pawls in engagement with the ratchet.
- 25 2. In a power driven post hole auger for use on a self-propelled power unit, having an auger-suspending frame, a vertically reciprocable auger suspended from the suspending frame, pawl and ratchet mechanism connecting the auger and said frame for causing raising and lowering of the auger, and a safety stop for holding a pawl out of engagement with the ratchet whereby to render the raising mechanism non-operative to cause further raising of the auger after it has reached a predetermined fixed point in its course of upward travel.
- 30 3. In a power driven post hole auger to be mounted on a self-propelled power unit, having an auger-suspending frame, a vertically reciprocable auger suspended from the suspending frame; the combination of pawl and ratchet mechanism connecting the auger and frame for causing raising and lowering of the auger, and a safety stop for holding a pawl out of engagement with the ratchet whereby to render the raising mechanism non-operative to cause further raising of the auger after it has reached a predetermined fixed point in its course of upward travel, said stop comprising an abutment connected with the upper part of the auger and travelling upwardly and downwardly therewith, a pendulant, vertically reciprocable link to be engaged by the abutment as the auger is raised, and a guard connected with the link and moving therewith, said guard, when the auger approaches the upper end of its course of travel, being moved into a position to prevent actuating contact between the ratchet and the pawl which engages it to cause raising of the auger.
- 35 4. In a digger of the class stated comprising a pendularly mounted, vertically reciprocable auger, and supporting means for the auger; means for reciprocating the auger, said last named means including a link pivotally connected to the supporting means, said link being pivotally supported to swing horizontally in a vertical plane, a lever pivotally connected at one end intermediate the
